United States Patent Office

Des. 193,836
Patented Oct. 16, 1962

193,836

DOOR KNOCKER OR SIMILAR ARTICLE

Mary J. Block, Rte. 1, Box 118, Coeur d'Alene, Idaho

Filed Apr. 17, 1961, Ser. No. 64,785

Term of patent 7 years

(Cl. D10—7)

FIG. 1 is a front elevational view of a door knocker or similar article embodying my new design;

FIG. 2 is a rear elevational view thereof;

FIG. 3 is a side view taken from the left in FIG. 1;

FIG. 4 is a top view thereof; and

FIG. 5 is a bottom view thereof.

I claim:

The ornamental design for a door knocker or similar article, as shown.
